UNITED STATES PATENT OFFICE

GUSTAV SCHWORETZKY, OF ESSLINGEN A. N., GERMANY, ASSIGNOR, BY MESNE ASSIGNMENTS, TO THE FIRM JFFA GES. M. B. H., OF BERLIN, GERMANY

HIGH-PRESSURE GAS-DEVELOPING CARTRIDGE

Application filed October 11, 1926, Serial No. 140,967, and in Germany October 21, 1925.

My invention relates to a high-pressure gas-developing cartridge or bottle for portable fire extinguishers as well as for the preparation of sparkling beverages in bottles in which the perfectly tight closure is effected merely by forcing a tapering part into a preferably tapering bore in or over the tapering end of another part consisting of the same material. The seal thus produced which is able to withstand hundreds of atmospheres of pressure without becoming untight is not produced by grinding one part accurately into or over the other in the manner of airtight glass stoppers or caps, but by the molecular eating of one part into the other, the parts consisting preferably of soft iron.

The simplest seal according to my invention is produced by forcing a plug or truncated cone into the correspondingly shaped bore in the neck of the cartridge. In gas cartridges in which the closing as well as the opening should take place at the charging place the part forced into the bore of the neck of the cartridge is a bushing in the form of a receptacle the bottom of which is so thin that it may be destroyed by driving in a striking pin.

Some embodiments of my invention are illustrated in the drawing affixed hereto.

30 In the drawing shows:

Fig. 1, a sectional elevation of a cartridge in which a tubular bushing is employed as closing part,

Fig. 2, a longitudinal section through the lower portion of a cartridge for a fire extinguisher in which a solid plug is employed for closing the cartridge,

Fig. 3, the closed charging opening according to Fig. 1 on a larger scale,

40 Fig. 4, a longitudinal section through the bushing employed in Figs. 1 and 3, and

Fig. 5, a small cartridge for the manufacture of a sparkling beverage in a siphon in sectional elevation.

45 Like parts are indicated by like letters of reference in all the figures of the drawing.

Referring to the drawing *b* is a sealing member forced into or over the opening of the cartridge. In the fire extinguisher cartridge according to Figs. 1, 2 and 3 this clos-

ing member is secured in the working position by a screw *s*. As shown in Figs. 1, 3 and 4 the enlarged inner end of the closing member *b* is fitted into a recess in the screw *s*. The bottom *d* of the closing member *b* is so thin that it forms a mere membrane and may be perforated or destroyed by the striking pin *i*. This pin *i* is guided at one end by the locking screw *s* and at the other end it is riveted into the diaphragm *m* soldered on and protecting the opening mechanism of the bottle. When the cartridge is rendered operative by forcing the striking pin into it this diaphragm is also driven inwards.

In the small siphon cartridge illustrated in Fig. 5 the member *b* is employed in such a manner that it is not forced into the cartridge neck but over it.

Various changes may be made in my improved cartridge within the ambit of my claims without departing from the spirit of my invention or sacrificing any of its advantages.

I claim as my invention:—

1. In a high-pressure gas developing cartridge for a portable fire extinguisher a sealing device for the charge opening, comprising in combination, a tapering bushing with thin bottom, fitting into the tapering bore of the charge opening, a screw for locking said bushing in place, a diaphragm soldered to the mouth of said charge opening, and a striking pin riveted at one end into said diaphragm and guided at the other end in said locking screw.

2. A closure for metal containers comprising plug and socket members having complementary wedging sealing faces, said members being composed of metals which will interpenetrate molecularly when forced together, and means for forcing the members into sealing relation.

3. A closure for high-pressure gas cartridges comprising plug and socket members having complementary wedging sealing faces and communicating bores, a destructible diaphragm closing one of said bores, said members being composed of metals which will interpenetrate molecularly when forced

together, and means for forcing the members into sealing relation.

4. A closure for metal containers as defined in claim 3, the plug member consisting of a tapered bushing and the socket member consisting of a tapered charge opening on the container.

In testimony whereof I affix my signature.
GÜSTAV SCHWORETZKY.
